US00D765616S

(12) **United States Design Patent** (10) Patent No.: **US D765,616 S**
(45) Date of Patent: **** Sep. 6, 2016**

(54) **PORTABLE SPEAKER**

(71) Applicant: **Ningbo Prosound Electronics Co., Ltd.**, Fenghua, Zhejiang (CN)

(72) Inventor: **Alexis Corval**, Zhejiang (CN)

(73) Assignee: **Ningbo Prosound Electronics Co., Ltd.** (CN)

(**) Term: **14 Years**

(21) Appl. No.: **29/525,899**

(22) Filed: **May 4, 2015**

(51) LOC (10) Cl. **14-01**

(52) U.S. Cl.

USPC **D14/204**
